H. J. HAMMANN

JAR COVER REMOVER

Filed Mar. 6, 1922

Fig. 1

Henry J. Hammann Inventor

By Philip T. Storrell

1120

UNITED STATES PATENT OFFICE.

HENRY J. HAMMANN, OF OMAHA, NEBRASKA.

JAR-COVER REMOVER.

Application filed March 6, 1922. Serial No. 541,415.

To all whom it may concern:

Be it known that HENRY J. HAMMANN, a citizen of the United States, residing at Omaha, in the county of Douglas and State 5 of Nebraska, has invented certain new and useful Improvements in Jar-Cover Removers, of which the following is a specification, reference being had therein to the accompanying drawing.

10 The invention relates to jar cover removers and has for its object to provide a device of this character comprising a pair of pliers of the cross handle type and the adjustable type, said pliers having their ends 15 detachably connected to a flexible jar cover holding loop, said loop being provided with teeth for biting into and holding the cover. Also to provide a toothed wedge block disposed between the jaws and adapted to be 20 forced inwardly by said jaws for engaging the jar cover for additionally holding the same when the jaws of the pliers are closed.

With the above and other objects in view the invention resides in the combination and 25 arrangement of parts as hereinafter set forth, shown in the drawings, described and claimed, it being understood that changes in the precise embodiment of the invention may be made within the scope of what is 30 claimed without departing from the spirit of the invention.

In the drawings:—

Figure 1 is a top plan view of the jar cover-remover.

35 Figure 2 is an enlarged perspective view of the jaw ends of the crossed members. Referring to the drawings, the numeral 1 designates a pair of pliers of the cross handle type and 2 the cross members forming 40 said pliers. The cross members 2 are connected together at 3 in such a manner that said jaws may be adjusted in relation to each other, thereby allowing the jaws 4 to be positioned for different sizes of jar cov- 45 ers 5. The jaws 4 adjacent their outer ends are provided with apertures 6, to which apertures the ends 7 of the flexible jar cover engag- 50 ing loop 8 extends and are held against movement by nuts 9. The looped member 8 adjacent its angled ends 7 extends through recesses 10 in the ends of the jaws 4 thereby preventing pivotal action of the loop 8 in relation to the jaws during a jar cover removing operation or when the device is being 55 placed in position. The loop 8 has its inner

periphery provided with teeth 11 which bite into the cover for securely gripping the cover during a wrenching operation.

Disposed between the jaws 4 is a wedge shaped block 12, the outer end 13 of which is provided with teeth, which teeth when the jaws are forced together and the wedge block 12 forced forwardly engage the side of the cover and force the same into the loop 8, thereby insuring the proper gripping of the 65 cover around its entire periphery by the toothed loop 8. The wedge block 12 is maintained in position between the jaws 4 by means of crossed arms 14, one end of which is connected pivotally at 15 to the jaws 4 70 and the other end provided with slots 16, which slots have passing therethrough a screw 17 carried by the wedge block 12, said screw 17 being provided with a thumb nut 18, by means of which thumb nut the frictional 75 holding of the wedge block 12 may be varied. When the jaws 4 are forced together the threaded screw 7 will move longitudinally in the slots 16 of the arms 14 thereby allowing the block to move to operative position. 80 Arms 14 primarily form means for supporting and holding the wedge block 12 in opposite position between the jaws 4, however they are held on the jaws 4 detachably, thereby allowing the wedge block to be entirely 85 removed from between the jaws, and by providing the nuts 9 for holding the loop 8, said loop may be also removed thereby allowing the pliers to be used for other purposes. 90

From the above it will be seen that a jar cover remover is provided which is simple in construction, and one wherein the parts have been reduced to a minimum.

The invention having been set forth what 95 is claimed as new and useful is:—

1. A jar cover remover comprising a pair of crossed members thereby forming hand gripping members and jaw members, a flexible loop having its ends attached to the 100 ends of the jaws, a wedge block disposed between the jaws, arms carried by the jaws and supporting said wedge block in such a manner that it may be moved longitudinally, said connections between the ends of 105 the jaw engaging loop and the jaws forming means for maintaining the crossed members and the cover engaging loop in the same horizontal plane.

2. A jaw cover remover comprising a pair 110

of crossed members thereby forming hand gripping members and jaw members, a flexible loop, the ends of said flexible loop being disposed in recesses in the ends of the 5 jaws and extending through apertures in said jaws, a wedge block disposed between the jaws and supported therebetween and means whereby the crossed members may be adjusted in relation to each other for adjusting the jaws in relation to each other. 10 In testimony whereof I hereunto affix my signature.

HENRY J. HAMMANN.
